UNITED STATES PATENT OFFICE.

CHARLES H. SHEPARD, OF BROOKLYN, NEW YORK, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 727,216, dated May 5, 1903.

Application filed January 16, 1901. Serial No. 43,456. (No model.)

To all whom it may concern:

Be it known that I, CHARLES H. SHEPARD, a citizen of the United States, and a resident of the borough of Brooklyn, city of New York, in the county of Kings and State of New York, have invented certain new and useful Improvements in Type-Writing Machines, of which the following is a specification.

My invention relates to the "case-shifting" mechanisms of type-writing machines in which a single set of keys is employed for writing two or more sets of characters and in which a shift-key is operated to effect a relative transverse movement between the paper and the types. It is difficult when operating at high speed to so time the successive operations of the shift-key and the type-keys as that the capital letters shall appear in their proper alinement with relation to the lower-case letters which follow them. If there is a sluggish movement of the shifting mechanism or a premature operation of the type-key, either the impression of the type appears out of alinement or else a blurred and unintelligible impression is made upon the paper, including part of the capital type and part of the lower-case type. In correcting such mistakes the appearance of the page is marred and much time and labor consumed. Still other faulty operations are liable to occur in some case-shift machines, such as the clashing or interlocking of parts.

It is the object of my invention to overcome all of these objections and to provide simple and effective means for preventing the types from printing until after the completion of the shifting operation.

To this end my invention consists, broadly, in the combination, with type-keys and a shift-key, of means operated by the shift-key for blocking or preventing the operation of the type-keys.

My invention also consists in a novel form of hinge for the shifting-platen carriage of a type-writing machine; and it further consists in certain features of construction, combinations of devices, and arrangements of parts, all as will be hereinafter fully set forth, and particularly pointed out in the concluding claims.

In the accompanying drawings, Figure 1 is a view, partly in section, of the right-hand side of a Remington No. 6 type-writing machine, showing my improvements applied thereto, the parts being in normal position. Fig. 2 is 55 a detail view of a key-locking device. Fig. 3 is an elevation, partly in section, of the left-hand side of said machine, showing the shifting operation in progress. Fig. 4 is a cross-section of the machine. Fig. 5 is a detail of the platen-frame hinge. Fig. 6 is a plan showing the platen-frame, the carriage or truck, and the new hinge construction, one of the hinges being in section.

In the several views similar parts are designated by similar numerals of reference, and certain portions are omitted or broken away to more clearly disclose the invention.

The framework of the machine comprises a base 1, corner-posts 2, and a top plate or type-ring 3. Upon the latter are mounted type-bars 4, connected by links 5 to key-levers 6, which are pivoted at 7 in the base and provided with keys 8 and returning-springs 9. The type impressions are made upon a platen 10, which is journaled at 11 in a platen-frame comprising end bars 12 13, front bar 14, and rear bar 15. Said platen is connected in rear by a double hinge to a truck 16, whose wheels 17 run upon a fixed guide-rail 18. At its forward portion the platen-frame has a roll 19, which runs upon a shift-rail 20, the latter being supported upon rocker-arms 21, which are fixed upon a rock-shaft 22, journaled in lugs 23, depending from the top plate. The 85 carriage is provided with a rack 24, which meshes with a pinion 25, suitably connected to an escapement-wheel 26. Dogs 27 and 28 co-operate with said wheel to control the letter-feeding movements of the carriage under 90 the tension of a spring-barrel, (not shown,) said dogs being mounted upon a rocker 29, which is pivoted at 30 in a bracket 31 and which has a forwardly-extending arm 32, provided with lateral branches 33. Upon these 95 branches is hung, by means of hooks 34, a universal bar 35, extending transversely beneath the key-levers and in the path of the latter, so that when any lever is depressed to swing its type-bar to print said universal 100

- bar is carried down, the dog-rocker is rocked, and the dogs 27 and 28 caused to assume a different relation to the escapement-wheel 26. When the type-key is released to permit the 5 return of the type-bar to normal position, the universal bar is lifted by a spring 36 and the dogs are returned to normal position, thereby permitting a feeding movement of the carriage.
- 10 The ordinary shift-key of the machine is designated 37 and is mounted upon a lever 38, pivoted at 39 between a pair of ears 40, supported at the left of the machine upon an inwardly-extending bracket 41, which is secured by a screw 42 to the side wall of the base. This lever 38 is connected by a strap 43 and link 44 to a pivot 45, which is so mounted upon the left-hand rocker-arm 46 of the platen-shifting frame that a depression 15 of the lever 38 pulls said pivot 45 downwardly and rocks the shifting-frame rearwardly, thus shifting the platen-frame to the position for printing capital letters or to upper-case position.
- 20 On the right-hand side of the machine is provided an auxiliary shift-key 47, mounted upon a lever 48, pivotally supported at 49 upon a bracket 50, secured to the right-hand side wall of the base by a screw 51. This lever 25 is connected by a link 52 to an extension 53, formed upon the right-hand rocker-arm 21.
- 25 Since all of the parts hereinabove mentioned excepting the platen-frame hinge are in common use upon the Remington No. 6 30 type-writing machine, it is not deemed essential to describe them more fully.
- 35 Just over the key-levers and substantially in the vertical plane of the universal bar 35 I mount a transverse horizontal rock-shaft 54. 40 Near the right-hand end thereof I mount an upwardly-extending catch, which is preferably composed of two parts 55 and 56, the latter being the shorter of the two and being pivoted at 57 to the lower main arm 55. These 45 two parts are connected by a spring 58, which is attached by a screw 59 to the arm 55 and secured at 60 to the part 56, thereby holding the latter normally in an upright position, while permitting it to yield in either direction.
- 50 Near the left-hand end of said shaft I mount a similar catch, the main arm thereof being designated as 61 and the shorter yielding part or finger as 56, and this catch likewise includes a spring, as 58. The fingers 55 56 occupy positions a trifle back of and below the ends of the branches 33 of the dog-rocker frame, so as normally not to interfere with the downward movement thereof; but when the catches are rocked upon the shaft 60 54 the downward movement of said frame, and hence the printing movements of the type-key levers and type-bars, is blocked or prevented. The arm 55 is connected by a forwardly-extending link 62 with the lower 65 end of an arm 63, which is attached to and extends downwardly from the right-hand op-

erating-arm 53 of the platen-shifting frame, so that whenever said frame is vibrated the arm 55 is swung forwardly, the rock-shaft 54 is rocked, and the other arm 61 is also swung 70 forwardly, both of the catch portions passing just beneath the branches 33.

In operation when the shift-key 37 is depressed the lever 38 is swung downwardly about its pivot 39 and through the link 44 75 and pivot 45 swings the entire shifting-frame 20 21 22 46, and thereby pushes the platen-frame rearwardly upon its hinge, so that the rear or capital letter upon the type carried at the end of the bar 4 may make an impression. During this movement the catches temporarily occupy positions directly beneath the branches 33 of the dog-rocker frame, as illustrated at Fig. 3, thereby preventing the normal or full operation of the dog-rocker, 80 universal bar, key-levers, and types, so that no printing can occur while the platen is in a midway position. The catches are swung far enough to escape the branches 33, so that the dog-rocker, and hence the keys and types, 85 may be operated in the usual manner. Upon releasing the shift-key from pressure the parts are returned to normal positions by means of the usual spring 64, and during said return the catches pass again beneath the 90 branches 33, so as to prevent premature operation thereof. Thus it will be seen that a type impression cannot be made during either the forward or backward shifting movements of the platen, so that it becomes impossible 95 for a double or blurred impression to be made or for the capital types to appear out of alignment with the lower-case types. Thus no matter how high the speed of operation or how poorly timed are the successive operations of the shift-key and the type-keys still 100 it is not possible for the operator to produce the faulty work hereinbefore referred to. Should the shift-key at any time be operated when a type-key is partly or fully depressed, 105 and hence when the branches of the dog-rocker 33 are in a depressed position, the pivoted and spring-controlled fingers 56 upon striking the said branches will yield, so that 110 no injury can be done either to the dog-rocker or to the catches and also so that the 115 shifting movement of the platen-frame may be effected.

The pivot 45, above referred to, is mounted, 120 as usual, upon a lever 65, which is pivoted at 66 to a depending portion 67 of the rocker-arm 46 of the shifting-frame. Pivoted at 68 to another depending portion 69 thereof is a handle or lever 70, having an arm 71, which has a finger 72, working in a slot 73, formed 125 in said lever 65. Said handle 70 also has an arm 74, to which is connected the upper end of said spring 64, the latter at its lower end being caught into a screw-eye 75, tapped into a portion of the framework. Upon swinging 130 the lever 70 upwardly about the pivot 68 the finger 72 thereon swings the lever 65 for-

wardly, and at the same time the arm 74 carries the spring over the dead-center 68, whereby the shifting frame and the platen-frame are normally held by said spring in their rearward or capital printing positions and whereby the shift-key 37 may be operated to shift the platen forwardly when required, all as usual in the Remington No. 6 machine. At this time the catches stand forwardly of the branches 33 and during an operation of the shift-key 37 are swung rearwardly. Hence it will be seen that when the machine is set for printing either lower-case or capital letters the operation of the type-keys is prevented during the movement of the shifting mechanism to go from one case to another. The parts are so constructed and timed that the catches or stops, which normally remain out of operative relation to the dog-rocker, so as to permit the operation of the character-keys for printing purposes in one case, come into an intercepting position relatively to said dog-rocker immediately the shift-key is started and hold said rocker and its associated parts against movement until the completion of the shifting operation, and hence the operator is prevented from printing a type of the other case until the platen has been shifted sufficiently to insure the striking of such type in alinement with the other types previously impressed or subsequently to be printed in the same line, and it will also be observed that on release of the shift-key the stops or catches again coact with the dog-rocker to prevent printing of a type before the shifting mechanism has been fully restored to its normal position and the platen likewise brought back to its normal position. Thus neither during the shifting nor returning movements of the platen can a type be printed out of line or be printed between lines either in whole or in part.

It will be understood that my invention is applicable as well to machines where instead of the platen the types are shifted either singly or all together.

Referring now to the platen-frame hinge-joint, it will be seen that I have changed the usual Remington No. 6 construction. In said machine the platen-frame is hinged upon the upper ends of a pair of rocker-arms 76, which are pivoted at 77 in the ends of the truck 16 and are united by a rock-shaft 78. In the upper end of each of these arms I tap a horizontal hole for a screw 79, having a prolonged outwardly-extending head 80 of reduced diameter for coaction with the usual adjustable stops 81 whereby the shift movements of the platen-carrier are limited. Said screw is provided at its inner end with a cylindro-conical point 82, which is seated in a pivot-hole 83, formed in a lug 84, cast upon the platen-frame. The screw may be adjusted longitudinally, so as to move the platen-frame endwise relatively to the truck 16, whereby the type impressions are enabled to

register exactly with the platen-scale usually placed upon said platen-frame. Said screws may also be adjusted so as to take up wear and prevent endwise shake of the platen-frame, and at the same time said screws permit a free pivotal movement of said platen-frame, which is a great desideratum in this class of machines, because it is important that the parts move freely under the action of the shift-key, so as not to fatigue the operator, and it is also important that the parts move accurately or without end shake and skewing in order to produce alined and evenly-spaced work. The outer portion of the screw-point 82 is cylindrical, while the inner portion (designated as 82²) is conical. The cylindrical shape of the screw-points insures that the joint will wear a long time, while the conical portion enables the wear to be taken up. A binding-nut 86 is provided for said screw and bears against the inner face of the arm 76.

Numerous changes in details of construction and arrangement may be made within the scope of my invention in adapting the same to various styles of machines, and parts of the invention may be used without others.

What I claim as new, and desire to secure by Letters Patent, is—

1. In a type-writing machine, the combination of a series of types, a platen, means for impressing the types on the paper on said platen, a case-shift mechanism for moving the types and platen relatively to one another and in a direction transverse to the length of the platen, and means for blocking the type-impressing movements during the operation of the case-shift mechanism.

2. In a type-writing machine, the combination of a platen, a series of pivoted type-bars, means for effecting printing movements of said types, a case-shift mechanism for changing the relation between the pivotal centers of the type-bars and the printing-center on the platen, and means controlled by said case-shift mechanism for blocking the printing movements of the types.

3. In a type-writing machine, the combination of a series of keys, a series of type-carriers each of which has a plurality of types thereon, a platen, means for effecting printing movements of said types, means for changing the printing-center, and means for automatically blocking the printing movements of said types during a changing of the printing-center.

4. In a type-writing machine, the combination of a series of types, a platen, means for shifting said platen, and means for simultaneously blocking the operation of said types.

5. In a type-writing machine, the combination of a type mechanism, means for effecting a printing movement of said type mechanism, a platen, a case-shift mechanism for shifting said platen, and a device connected to said case-shift mechanism and caused at

the operation of the latter to get into the path of a part which is moved at the printing stroke of the type.

6. In a type-writing machine, the combination of a series of types, a series of keys therefor, a carriage, carriage escapement devices operated by said keys, a platen, a case-shift mechanism, and a catch operatively connected to said case-shift mechanism and arranged to block the operation of said carriage escapement devices and hence of said keys.

7. In a type-writing machine, the combination of a series of types, a series of keys, a carriage, an escapement mechanism therefor including a dog-rocker operated by said keys, a case-shift mechanism, and a catch connected to said case-shift mechanism and arranged in proximity to said dog-rocker.

8. In a type-writing machine, the combination of a platen, a series of types, means for effecting a printing movement of said types, a series of keys, mechanism for causing a relative shifting movement between said types and said platen, a vibratory device connected to said shift mechanism, and a part controlled by the keys and arranged to be intercepted by said vibratory device.

9. In a type-writing machine, the combination with a series of types and a platen, means for impressing the types on the platen, of a normally inactive catch adapted to block a part that moves in unison with all the types, a shift-key mechanism, and connections between said shift-key mechanism and said catch.

10. In a type-writing machine, the combination of a series of types, a platen, letter-feeding devices including a dog-rocker having branches, a universal bar suspended upon said branches, key-levers connected to said types and constructed to operate said universal bar, a rock-shaft, a pair of normally inactive catches upon said rock-shaft, and adapted to block the movement of said dog-rocker, and means connected to said rock-shaft for shifting said platen.

11. In a type-writing machine, the combination of a series of types, a series of key-levers connected thereto, a platen-carriage, escapement devices for said carriage controlled by said keys, rock-shaft 54, catches thereon, link 62, and a platen-shifting frame to which said link is connected.

12. In a type-writing machine, the combination with a series of types, a platen, and a case-shifting mechanism, of a flexible catch connected to said case-shift mechanism and arranged out of the path of a part which moves in unison with the types, and means for moving said catch into the path of said part.

13. In a type-writing machine, the combination of a series of types, a platen, a case-shift mechanism, a yielding finger connected to said case-shift mechanism and arranged out of the path of a part which moves in unison with the types, and means for causing

said finger to intercept said part during the operation of the case-shift mechanism.

14. In a type-writing machine, a catch connected to and moving with a case-shifting mechanism and comprising two parts, one yieldingly pivoted upon the other and occupying a normal position just out of the path of a part which moves in unison with type-impressing devices. 75

15. In a type-writing machine, the combination with a series of types, a platen, a carriage, escapement devices, including a dog-rocker, and a platen-shifting mechanism, of rock-shaft 54, arms 55 and 61 thereon, yielding fingers 56 carried by said arms and adapted to get into the path of said dog-rocker, and links 62 connecting one of said arms to the case-shift mechanism. 80

16. In a case - shifting and key - blocking mechanism, the combination of rock-shaft 54, arms 55 and 61 thereon, fingers 56 pivoted on said arms, springs 58, and means connected to the case-shift mechanism for rocking said shaft. 85

17. In a type-writing machine, a paper-carriage comprising a truck, rocker - arms thereon, a platen-frame, pivots whereby said platen - frame is hinged upon said rocker-arms, and means for moving said pivots so as to adjust said platen-frame longitudinally of said truck. 90

18. In a type-writing machine, the combination, in a paper-carriage, of a truck, rocker-arms hinged upon the truck, and a platen-frame hinged upon said rocker-arms by means of endwise-adjustable screw-points. 100

19. In a type-writing machine, the combination in a paper-carriage, of a truck, rocker-arms hinged upon the truck, a platen-frame 105 hinged upon said rocker-arms by means of endwise-adjustable screw-points, and binding-nuts for said screws.

20. In a type - writer paper-carriage, the combination of truck 16, rocker-arms 76, shaft 110 78 connecting said rocker - arms, screws 79 tapped into said rocker - arms and having bearing-points, and a platen-frame arranged between and hinged upon said points. 115

21. In a type - writer paper-carriage, the combination of truck 16, rocker-arms 76, shaft 120 78 connecting said rocker-arms, screws 79 tapped into said rocker - arms and having points, a platen-frame arranged between and hinged upon said points, and heads 80 upon said screws for coöperation with stops 81 upon said truck. 125

22. In a type - writer paper-carriage, the combination of truck 16, rocker-arms 76, shaft 125 78 connecting said rocker - arms, screws 79 tapped into said rocker - arms and having points, a platen-frame arranged between and hinged upon said points, heads 80 upon said screws for coöperation with stops 81 upon said truck, and binding-nuts 86. 130

23. In a type - writer paper-carriage, the combination of a truck, a platen-frame, a

hinge mechanism whereby said platen-frame is connected to said truck, said hinge mechanism including a pair of oppositely-disposed screws having partly-cylindrical and partly-conical points.

Signed in the borough of Manhattan, city of New York, in the county of New York and

State of New York, this 15th day of January, A. D. 1901.
